UNITED STATES PATENT OFFICE.

HOLMES MARSHALL, OF CLEVELAND HEIGHTS, OHIO.

SEAL LOCK.

Application filed May 16, 1927. Serial No. 191,573.

This invention relates to seal locks, and particularly to those having a sealing member in the nature of a card which normally covers the keyhole and must be mutilated before the key can be used to open the lock. The lock embodying my invention is especially adapted for use in locking boxes, containers, grips, satchels and the like, and is advantageous in that it indicates whether or not the satchel or other container has been opened by an unauthorized person. Moreover the card, carrying the owners' name, furnishes a readily visible means of identification, very useful when the satchel is carried by a porter or whenever it is left in a public place, such as a check room.

An object of the present invention is to make a lock of this character which is simple in construction and which may be readily designed for easy attachment to portable traveling bags. The lock made in accordance with my invention is so designed that the owners' card may constitute the sealing member and thereby serve also as a means of identification.

One form of mechanism for carrying out my invention is illustrated in the drawings wherein Fig. 1 is a view of one form of the lock closed; Fig. 2 is a similar view showing the cover in partly open position (as indicated in broken lines in Fig. 4) and with the seal mutilated; Fig. 3 is a view showing the interior lock mechanism; Fig. 4 is a section taken through the lock on a plane indicated by the line 4—4 in Fig. 2; Fig. 5 is an elevation of a safety deposit box equipped with a sealed lock made in accordance with my invention; Fig. 6 is a side elevation of a satchel embraced by a chain carrying my seal lock.

The form of seal lock which I have shown in Figs. 1 to 6 inclusive comprises a hollow casing 10 which has an opening 11 along one side and an opening 12 adjacent one end thereof. A bolt 13 is slidably mounted within the casing and has keeper portions 14 and 15 associated therewith. Any suitable form of mechanism may be utilized for locking the bolt in closed position when it is snapped shut, but that illustrated comprises a spring 16, one end of which is attached to the casing, and the other end of which, is adapted to engage a notch 17 in the bolt and to hold the bolt in locked position. The spring may be moved out of engagement with the bolt and the bolt may then be moved to open position upon the turning of a key 18 which is inserted through the keyhole 19.

A cover 20 is illustrated as being hinged at 21 to one end of the casing and as having downturned flanges on three sides thereof which extend over the edge of the casing when the cover is closed. The cover also has a sight opening 22 behind which a card 23 may be placed before the cover is closed. This card normally covers the keyhole and thereby prevents access to the opening, unless the card is mutilated, so long as the cover is locked.

To lock the cover to the casing, I have shown the cover as having an opening 25 in the flange portion 26. When the cover is closed, the keeper 15 extends through this opening and also through an opening in the casing in registration with the opening 25. The locked position of the bolt is shown in Fig. 4.

To lock the device described to a container such as a hand bag, I have shown an opening 30 extending along one side of the casing and I have illustrated the keeper 14 as being arranged to project across the opening and to enter the passageway 31 in a flange 32. The container to be locked may have a staple or similar fastener which enters the opening 30 and is locked when the keeper 14 is moved to the locked position. Or, as in the case of the satchel S in Fig. 6, the bolt 14 may pass through the end link of a chain C anchored to the lock and surrounding the container. Thus, the container as well as the seal is locked by a single movement of the bolt.

In Fig. 5, I have shown my invention as applied to a safety deposit box 35. In this arrangement the casing is attached to the front wall of the box in such manner that the side having the opening 30 is adjacent the upper edge of the front wall 36. The keeper 14^a when in locked position will then pass through the staple 37 which is fastened to the casing and through another staple 38 which is fastened to the box lid 39. The sealed cover 20^a is locked simultaneously with the locking of the box in the same manner as that heretofore described.

The box lid may have a flange 40 which extends downwardly over the lid 20^a and functions to prevent removal of the lock as a unit from the wall of the box so long as the box is locked.

A device made in accordance with my invention is advantageous in that it provides a simple and effective means for locking a portable container, and at the same time insures protection against surreptitious opening of the container. The card which closes the key-

hole functions then, not only to appraise the owner of the condition of the container but also serves as a ready means of identification. As applied to safety deposit boxes my invention makes a simple form of lock which obviates the necessity for an extra key in the hands of the custodian, since the owner may make any indicia of his own design on the hidden surface of the card.

10 1. I claim:—

15 1. In a device of the character described, the combination of a casing, a hinged cover therefor having a sight opening, said cover being adapted to hold a card between it and the casing, a locking bolt movably mounted in the casing and serving the double purpose of locking a suitable container and simultaneously locking the cover to the casing, said locking bolt being controlled by the key in a 20 region shielded by the card.

2. In a device of the character described, the combination of a casing, a hinged cover therefor, having a sight opening, said cover being adapted to hold a card between it and the casing, a locking bolt movably mounted in the casing and serving the double purpose of locking a suitable container and simultaneously locking the cover to the casing, and spring means adapted to hold the bolt in 25 locked position when snapped shut, said locking bolt being controlled by the key in a region shielded by the seal.

3. The combination of a lock casing, a lock bolt therein, a cover hinged to the casing, said bolt being adapted to perform the double function of locking a container and locking the cover to the casing, a key for releasing the bolt cooperative with a keyhole, located behind a sight opening in the cover, whereby the 30 cover may clamp, against the casing, a card covering the keyhole.

4. A device of the character described

comprising in combination, a casing having a keyhole opening therein, a lid associated with the casing and having a sight opening therein, a frangible replaceable member disposed behind said sight opening and covering the keyhole opening, a bolt carried within the casing having portions adapted for simultaneously to lock the lid to the casing and the casing to a container, whenever the bolt is actuated in one direction.

5. A device of the character described comprising in combination a hollow rectangular casing having openings in one side, and in one end thereof, a key actuated bolt having a portion thereof passing through each opening, a cover hinged to the casing and having an opening therein, a frangible member between the cover and casing and arranged to cover the keyhole in the casing when the cover is closed; said bolt having one of said portions adapted to lock the cover to the casing and simultaneously to lock the casing to a container.

6. A lock, comprising in combination, a hollow casing having openings in one side and one end thereof, a cover hinged to the casing and having a flange thereon extending downwardly along the marginal edges of the casing, said cover having an opening registering with the opening in the end of the casing, a key actuated bolt mounted within the casing, having a portion thereof passing through each opening in the casing, said casing having a key hole therein, said cover having a sight opening in registration with said key hole, a frangible member passing between the cover and casing and functioning normally to close the key hole and sight opening when the cover is locked to the casing.

In testimony whereof, I hereunto affix my signature.

HOLMES MARSHALL.
